SPEAR GUN

Johnie L. Carroll, 611 Wilshire Blvd., Hawthorne, Calif.

Filed Feb. 13, 1961, Ser. No. 63,931

Term of patent 14 years

(Cl. D30—1)

FIG. 1 is a side elevational view of a spear gun embodying my new design;

FIG. 2 is an elevational view of the reverse side of FIG. 1;

FIG. 3 is a plan view of FIG. 1;

FIG. 4 is a right end elevation of FIG. 1;

FIG. 5 is a left end elevation of FIG. 1; and

FIG. 6 is a fragmentary section taken on line 6-6 of FIG. 1.

I claim:

The ornamental design for a spear gun, substantially as shown.
